(57) **CLAIM**

The ornamental design for a breast pump flange, as shown and described.

DESCRIPTION

FIG. 1 is a perspective view of the top and front of a first embodiment of the breast pump flange;

FIG. 2 is a perspective view of the bottom and rear of the first embodiment of the breast pump flange;

FIG. 3 is a front view of the first embodiment of the breast pump flange;

FIG. 4 is a rear view of the first embodiment of the breast pump flange;

FIG. 5 is a right side view of the first embodiment of the breast pump flange;

FIG. 6 is a left side view of the first embodiment of the breast pump flange;

FIG. 7 is a top view of the first embodiment of the breast pump flange;

FIG. 8 is a bottom view of the first embodiment of the breast pump flange;

FIG. 9 is a perspective view of the top and front of a second embodiment of the breast pump flange;

FIG. 10 is a perspective view of the bottom and rear of the second embodiment of the breast pump flange;

FIG. 11 is a front view of the second embodiment of the breast pump flange;

FIG. 12 is a rear view of the second embodiment of the breast pump flange;

FIG. 13 is a right side view of the second embodiment of the breast pump flange;

FIG. 14 is a left side view of the second embodiment of the breast pump flange;

(Continued)

FIG. 15 is a top view of the second embodiment of the breast pump flange;
 FIG. 16 is a bottom view of the second embodiment of the breast pump flange;
 FIG. 17 is a perspective view of the top and front of a third embodiment of the breast pump flange;
 FIG. 18 is a perspective view of the bottom and rear of the third embodiment of the breast pump flange;
 FIG. 19 is a front view of the third embodiment of the breast pump flange;
 FIG. 20 is a rear view of the third embodiment of the breast pump flange;
 FIG. 21 is a right side view of the third embodiment of the breast pump flange;
 FIG. 22 is a left side view of the third embodiment of the breast pump flange;
 FIG. 23 is a top view of the third embodiment of the breast pump flange;
 FIG. 24 is a bottom view of the third embodiment of the breast pump flange;
 FIG. 25 is a perspective view of the top and front of a fourth embodiment of the breast pump flange;
 FIG. 26 is a perspective view of the bottom and rear of the fourth embodiment of the breast pump flange;
 FIG. 27 is a front view of the fourth embodiment of the breast pump flange;
 FIG. 28 is a rear view of the fourth embodiment of the breast pump flange;
 FIG. 29 is a right side view of the fourth embodiment of the breast pump flange;
 FIG. 30 is a left side view of the fourth embodiment of the breast pump flange;
 FIG. 31 is a top view of the fourth embodiment of the breast pump flange;
 FIG. 32 is a bottom view of the fourth embodiment of the breast pump flange;
 FIG. 33 is a perspective view of the top and front of a fifth embodiment of the breast pump flange;
 FIG. 34 is a perspective view of the bottom and rear of the fifth embodiment of the breast pump flange;
 FIG. 35 is a front view of the fifth embodiment of the breast pump flange;
 FIG. 36 is a rear view of the fifth embodiment of the breast pump flange;

FIG. 37 is a right side view of the fifth embodiment of the breast pump flange;
 FIG. 38 is a left side view of the fifth embodiment of the breast pump flange;
 FIG. 39 is a top view of the fifth embodiment of the breast pump flange; and,
 FIG. 40 is a bottom view of the fifth embodiment of the breast pump flange.
 The broken lines in the drawings depict portions of the breast pump flange that form no part of the claimed design.
